(57) **CLAIM**

The ornamental design for an electrosurgical device with a curve, as shown and described.

DESCRIPTION

FIG. 1 is a front, left and top perspective view of an electrosurgical device with a curve showing our new design;

FIG. 2 is a left side view of the electrosurgical device of FIG. 1;

FIG. 3 is a rear view of the electrosurgical device of FIG. 1; FIG. 4 is a front view of the electrosurgical device of FIG. 1;

FIG. 5 is a right side view of the electrosurgical device of FIG. 1;

FIG. 6 is a bottom plan view of the electrosurgical device of FIG. 1;

FIG. 7 is a top plan view of the electrosurgical device of FIG. 1;

FIG. 8 is a front, left and top perspective view of an alternative embodiment of an electrosurgical device with a curve;

FIG. 9 is a left side view of the electrosurgical device of FIG. 8;

FIG. 10 is a rear view of the electrosurgical device of FIG. 8;

FIG. 11 is a front view of the electrosurgical device of FIG. 8;

FIG. 12 is a right side view of the electrosurgical device of FIG. 8;

FIG. 13 is a bottom plan view of the electrosurgical device of FIG. 8;

FIG. 14 is a top plan view of the electrosurgical device of FIG. 8;

FIG. 15 is a front, left and top perspective view of an alternative embodiment of an electrosurgical device with a curve;

FIG. 16 is a left side view of the electrosurgical device of FIG. 15;

FIG. 17 is a rear view of the electrosurgical device of FIG. 15;

FIG. 18 is a front view of the electrosurgical device of FIG. 15;

FIG. 19 is a right side view of the electrosurgical device of FIG. 15;

FIG. 20 is a top plan view of the electrosurgical device of FIG. 15;

FIG. 21 is a bottom plan view of the electrosurgical device of FIG. 15;

FIG. 22 is a front, left and top perspective view of an alternative embodiment of an electrosurgical device with a curve;

(Continued)

FIG. 23 is a left side view of the electrosurgical device of FIG. 22;
 FIG. 24 is a rear view of the electrosurgical device of FIG. 22;
 FIG. 25 is a front view of the electrosurgical device of FIG. 22;
 FIG. 26 is a right side view of the electrosurgical device of FIG. 22;
 FIG. 27 is a top plan view of the electrosurgical device of FIG. 22; and,
 FIG. 28 is a bottom plan view of the electrosurgical device of FIG. 22.
 The broken lines immediately adjacent the shaded areas represent the bounds of the claimed design while all other broken lines are directed to environment and are for illustrative purposes only; the broken lines form no part of the claimed design.

The broken away symbols in FIGS. 1-2, 5-9, 12-16, 19-23 and 26-28 indicate that any portion of the article beyond what is shown forms no part of the claimed design.
